DESIGN FOR AN AIRPLANE OR THE LIKE

Robert J. Nebesar, Bristol, Va.

Original No. 129,412, dated September 9, 1941,
Serial No. 99,482, March 10, 1941, for 14 years.
Application for reissue November 21, 1941, Serial No. 104,246

Term of patent 14 years

To all whom it may concern:

Be it known that I, Robert J. Nebesar, a citizen of Czechoslovakia, residing at Bristol, in the county of Washington, in the State of Virginia, have invented a new, original, and ornamental Design for an Airplane or the like, of which the following is a specification, reference being had to the accompanying drawing forming a part thereof.

I claim:

The ornamental design for an airplane or the like, substantially as shown.

ROBERT J. NEBESAR.
